UNITED STATES PATENT OFFICE

JAMES OGILVIE, OF BUFFALO, NEW YORK, ASSIGNOR TO NATIONAL ANILINE & CHEMICAL COMPANY, INC., OF NEW YORK, N. Y., A CORPORATION OF NEW YORK

PRODUCTION OF N-DIHYDRO-ANTHRAQUINONEAZINES

No Drawing.

Application filed August 6, 1929. Serial No. 383,971.

This invention relates to a process for the production of N-dihydroanthraquinoneazines, and more particularly to the reduction of halogenated 1.2.2'.1'-anthraquinoneazines 5 to the corresponding N-dihydroazines.

An object of the invention is to provide a process whereby the reduction of anthraquinoneazines may be accomplished at a low temperature in a simple manner, efficiently and 10 economically, on a commercial scale.

Another object of the invention is to produce a vat dyestuff in a physical condition which makes it particularly advantageous in the dyeing of textiles by the pad and jig 15 (pigment padding) method.

Other objects of the invention will in part be obvious and will in part appear hereinafter.

The invention accordingly comprises the 20 several steps and the relation of one or more of such steps with respect to each of the others thereof, which will be exemplified in the process hereinafter disclosed, and the scope of the invention will be indicated in 25 the claims.

The conversion of 1.2.2'.1'-anthraquinoneazines to the corresponding N-dihydroazines has previously been accomplished by reduction with alkaline sodium hydrosulfite to the 30 leuco form and oxidation of the resulting leuco compound with air to the N-dihydroazine. A milder reduction of the 1.2.2'.1'-anthraquinoneazines produces intermediate compounds known as anthraquinoneazhydrides, and a stronger reduction of the 35 1.2.2'.1'-anthraquinoneazines, such as distillation with zinc dust, eventually eliminates the oxygen of the keto groups, producing anthracenazines as the final product. The anthraquinoneazine dyestuffs are usually marketed in the N-dihydroazine form.

In the practice of the present invention, 1.2.2'.1'-anthraquinoneazine, and derivatives 45 thereof which contain substituents in the anthraquinone nucleus, such as chlorine, bromine, alkyl, sulfo, amino, hydroxy, etc., may be reduced to the N-dihydroazine form by subjecting them to the reducing action of a 50 polyvalent metal in the presence of a mineral or inorganic acid excepting nitric acid.

In the reduction of certain anthraquinoneazines, particularly in the reduction of the anthraquinoneazines containing not more than two substituent halogen atoms in the anthraquinone nucleus, by the action of a 55 metal in the presence of the inorganic acid in the manner of the present invention, the conversion to the N-dihydroazine is accomplished without the elimination of substituents in the anthraquinone nucleus. Further, 60 when a halogenated anthraquinoneazine has been produced by the halogenation of the anthraquinoneazine in the presence of an acid, e. g., sulfuric acid, the reduction is carried out preferably by treating the crude halogenation mass with the finely divided metal. 65

As illustrative embodiments of a manner in which the invention may be carried out in practice, the following examples are presented. The parts are by weight. 70

Example 1.—350 parts indanthrene, containing about 93.4% of N-dihydro-anthraquinoneazine (.74 mols) are chlorinated at 34°-35° C., in 4550 parts of 94.5% sulfuric acid, by the introduction of 90 parts of chlorine gas (2.8 mols). The gas is introduced as fast as it is absorbed. The chlorination reaction mass which contains chlorinated N-dihydro-anthraquinoneazine, and also some chlorinated anthraquinoneazine, is then 75 cooled to about 20° C. and 8 parts of aluminum bronze (i. e., pulverized aluminum) are now added in small portions at a time, permitting the reaction to subside before adding each subsequent portion. During the reduction the temperature is permitted to rise to 28°-29° C. at which point it is maintained for about three hours after the last of the aluminum has been added, or until reduction is completed. The completion of the reduction may be detected by removing a sample of the reaction mass and placing it in water. 80 A blue violet precipitate indicates the completion of the reduction. When reduction is finished, the mass is added to 2150 parts of 85 water which has been preheated to 60° C., and is then further diluted with cold water, filtered and washed.

In this chlorination, there is produced a 90 mixture containing probably the azine, the 95

N-dihydroazine and the azhydine, hence the quantity of aluminum needed for the reduction will vary, depending upon the quantity of unreduced or inadequately reduced halogeno-indanthrene present in the chlorination mass. The quantity of aluminum needed for the reduction will be in the ratio of about $\frac{2}{3}$ of a gram atom of aluminum per gram molecule of anthraquinoneazine or azhydine present, but preferably an excess of aluminum is employed to insure complete reduction.

Although aluminum reacts very slowly with concentrated sulfuric acid alone, its action in the above reduction is vigorous and is accompanied by considerable evolution of heat. It is therefore desirable to control the temperature of the reduction in order to prevent mechanical loss of product due, for example, to foaming over, and to prevent a too vigorous reduction. When utilizing concentrated sulfuric acid, it is preferred to employ temperatures of about 25°-35° C., although higher temperatures may be employed. With dilute sulfuric acids higher temperatures may be attained without obtaining too vigorous reduction.

The excess of aluminum over that required for the reduction dissolves only slowly in the sulfuric acid. The presence of the excess of aluminum bronze in the dyestuff, especially where the dyestuff is to be made into a printing paste, is highly objectionable. Therefore, the reduction mass is drowned in water to produce a dilute solution of sulfuric acid which dissolves the excess of aluminum more readily. Preferably, the water used to dilute the reduction mass is preheated, for the speed of reaction between the aluminum and the sulfuric acid is accelerated by heating. Also, instead of using concentrated sulfuric acid, the reduction may be carried out by first diluting the chlorination mass then adding the metal with or without the aid of external heating. The reduction may also be accomplished in acids in which the indanthrene compounds are not soluble such as, for example, dilute sulfuric acid, or in hydrochloric acid.

Example 2.—60 parts of dibrom-anthraquinoneazine are dissolved in 600 parts of 93.1 per cent sulfuric acid at about 20° C., and 6.4 parts of copper dust are added in small successive portions as described in Example 1, the temperature being permitted to rise to about 29°-30° C. during the reaction. The reduction mass is agitated at 29°-30° C. until the reduction is complete, and is then drowned in 300 parts of water preheated to about 60° C., and then diluted with cold water, filtered and washed.

Example 3.—15 parts of trichloranthraquinoneazine are dissolved in 150 parts 66° Bé. sulfuric acid at about 20° C., and a 0.5 part of aluminum dust is added in small successive portions as described above, the temperature

being permitted to rise to about 29°-30° C. during the reaction. The reduction mass is agitated at 29°-30° C., until reduction is complete, and is then drowned in 75 parts of water, diluted with cold water, filtered and washed.

In a corresponding way, 1,2,2',1'-anthraquinoneazine, or derivatives thereof which contain other substituents in the anthraquinone nucleus such as alkyl, sulfo, amino, hydroxy, etc. may be reduced.

It will be understood of course that the invention in its broader aspect is not limited to the specific materials and amounts thereof set forth in the preceding examples. Other polyvalent metals, preferably those having an atomic number lying between 13 and 30 inclusive and which form soluble sulfates, such as, among others, zinc or iron may be used in the place of the aluminum or copper above specified. Whereas the quantity of aluminum has preferably been given above as $\frac{2}{3}$ rds of a gram atom per gram molecule of anthraquinoneazine it is to be noted that in the use of a bivalent metal, for example, copper, an equal molecular proportion of metal and anthraquinoneazine or azhydine is employed it being particularly desirable when using a bivalent metal to have an excess present. Furthermore, it is preferred in general to utilize the metals in finely divided form. However, if desired, coarser or granulated particles may be used.

The sulfuric acid used in the reduction may be replaced by other mineral acids. Hydrochloric acid is suitable for use at low temperatures; but, since it has a tendency to chlorinate the non halogenated indanthreneazines or the mono halogenated indanthreneazines, this acid is not suitable for the reduction at high temperatures of anthraquinoneazines containing less than two atoms of halogen, unless it is desired to produce a chlorinated N-dihydro-anthraquinoneazine.

The reduced dyestuffs obtained in the practice of the present invention are generally of an amorphous appearance when viewed under the microscope and are especially advantageous in the dyeing of textiles by the pad and jig method.

Since certain changes may be made in carrying out the above process without departing from the scope of the invention, it is intended that all matter contained in the above description shall be interpreted as illustrative and not in a limiting sense.

Having described my invention, what I claim as new and desire to secure by Letters Patent is:

1. A process for the production of N-di-hydro-anthraquinoneazines, which comprises subjecting an 1,2,2',1'-anthraquinoneazine in a concentrated mineral acid excepting nitric acid to the reducing action of a finely divided polyvalent metal having an atomic number

- between 13 and 30, inclusive, and which forms a soluble sulfate.
2. A process for the production of N-dihydro-anthraquinoneazines, which comprises subjecting an 1.2.2'.1'-anthraquinoneazine in concentrated sulfuric acid to the reducing action of a polyvalent metal having an atomic number lying between 13 and 30 inclusive and which forms a soluble sulfate.
- 5 3. A process for the production of an N-dihydro-anthraquinoneazine, which comprises subjecting an 1.2.2'.1'-anthraquinoneazine to the reducing action of aluminum and sulfuric acid.
- 10 4. A process for the production of an N-dihydro-anthraquinoneazine, which comprises subjecting an 1.2.2'.1'-anthraquinoneazine containing halogen as a substituent in the anthraquinone nucleus, to the reducing action of aluminum in the presence of sulfuric acid.
- 15 5. A process for the production of an N-dihydro-anthraquinoneazine, which comprises halogenating an 1.2.2'.1'-anthraquinoneazine in the presence of sulfuric acid and adding aluminum to the halogenation reaction mass to reduce the halogenated anthraquinonazine to the N-dihydro form.
- 20 6. A process for the production of an N-dihydro-anthraquinoneazine, which comprises introducing chlorine into a sulfuric acid solution of an 1.2.2'.1'-anthraquinoneazine, and after chlorination adding aluminum to the reaction mass to reduce the chlorinated anthraquinoneazine to the N-dihydro form.
- 25 7. A process for the production of N-dihydro-anthraquinoneazines, which comprises subjecting an 1.2.2'.1'-anthraquinoneazine in the presence of a mineral acid excepting nitric acid, to the reducing action of a polyvalent metal having an atomic number lying between 13 and 30 inclusive and which forms a soluble sulfate.
- 30 8. A process for the production of N-dihydro-anthraquinoneazines, which comprises subjecting an 1.2.2'.1'-anthraquinoneazine in the presence of sulfuric acid, to the reducing action of a polyvalent metal having an atomic number lying between 13 and 30 inclusive and which forms a soluble sulfate.
- 35 9. A process for the production of N-dihydro-anthraquinoneazines, which comprises subjecting an 1.2.2'.1'-anthraquinoneazine containing halogen as a substituent in the anthraquinone nucleus, in the presence of a mineral acid excepting nitric acid to the reducing action of a polyvalent metal having an atomic number lying between 13 and 30 inclusive and which forms a soluble sulfate.
- 40 10. A process for the production of N-dihydro-anthraquinoneazines, which comprises subjecting an 1.2.2'.1'-anthraquinoneazine containing halogen as a substituent in the anthraquinone nucleus, in the presence of sulfuric acid to the reducing action of a polyvalent metal having an atomic number lying between 13 and 30 inclusive and which forms a soluble sulfate.
- 45 11. A process for the production of N-dihydro-anthraquinoneazines, which comprises subjecting an 1.2.2'.1'-anthraquinoneazine containing chlorine as a substituent in the anthraquinone nucleus, to the reducing action of a polyvalent metal having an atomic number lying between 13 and 30 inclusive and which forms a soluble sulfate, in the presence of a mineral acid excepting nitric acid.
- 50 12. A process for the production of N-dihydro-anthraquinoneazines, which comprises subjecting an 1.2.2'.1'-anthraquinoneazine containing chlorine as a substituent in the anthraquinone nucleus, to the reducing action of a polyvalent metal having an atomic number lying between 13 and 30 inclusive and which forms a soluble sulfate, in the presence of sulfuric acid.
- 55 13. A process for the production of N-dihydro-anthraquinoneazines, which comprises subjecting an 1.2.2'.1'-anthraquinoneazine containing not more than two substituent halogen atoms in the anthraquinone nucleus, to the reducing action of a polyvalent metal having an atomic number lying between 13 and 30 inclusive and which forms a soluble sulfate, in the presence of a mineral acid excepting nitric acid.
- 60 14. A process for the production of N-dihydro-anthraquinoneazines, which comprises subjecting an 1.2.2'.1'-anthraquinoneazine containing not more than two substituent halogen atoms in the anthraquinone nucleus, to the reducing action of a polyvalent metal having an atomic number lying between 13 and 30 inclusive and which forms a soluble sulfate, in the presence of sulfuric acid.
- 65 15. A process for the production of N-dihydro-anthraquinoneazines, which comprises subjecting an 1.2.2'.1'-anthraquinoneazine containing not more than two substituent chlorine atoms in the anthraquinone nucleus, to the reducing action of a polyvalent metal having an atomic number lying between 13 and 30 inclusive and which forms a soluble sulfate, in the presence of a mineral acid excepting nitric acid.
- 70 16. A process for the production of N-dihydro-anthraquinoneazines, which comprises subjecting an 1.2.2'.1'-anthraquinoneazine containing not more than two substituent chlorine atoms in the anthraquinone nucleus, to the reducing action of aluminum and sulfuric acid.
- 75 17. A process for the production of N-dihydro-anthraquinoneazines, which comprises halogenating an 1.2.2'.1'-anthraquinoneazine in the presence of a mineral acid excepting nitric acid and adding to the halogenation reaction mass a polyvalent metal having an atomic number lying between 13 and 30 in-

clusive and which forms a soluble sulfate, to reduce the halogenated anthraquinoneazine to the N-dihydro form.

18. A process for the production of N-dihydro-anthraquinoneazines, which comprises halogenating an 1.2.2'.1'-anthraquinoneazine in the presence of sulfuric acid and adding to the halogenation reaction mass a polyvalent metal having an atomic number lying between 13 and 30 inclusive and which forms a soluble sulfate, to reduce the halogenated anthraquinoneazine to the N-dihydro form.

19. A process for the production of an N-dihydro-anthraquinoneazine, which comprises chlorinating an 1.2.2'.1'-anthraquinoneazine in the presence of a mineral acid excepting nitric acid and adding to the chlorination reaction mass a polyvalent metal having an atomic number lying between 13 and 30 inclusive and which forms a soluble sulfate.

20. A process for the production of an N-dihydro-anthraquinoneazine, which comprises chlorinating an 1.2.2'.1'-anthraquinoneazine in the presence of sulfuric acid and adding to the chlorination reaction mass a polyvalent metal having an atomic number lying between 13 and 30 inclusive and which forms a soluble sulfate.

21. A process for the production of N-dihydro-anthraquinoneazines which comprises subjecting an 1.2.2'.1'-anthraquinoneazine containing halogen as a substituent in the anthraquinone nucleus in concentrated sulfuric acid to the reducing action of aluminum.

In witness whereof, I have hereunto set my hand.

JAMES OGILVIE.
